UNITED STATES PATENT OFFICE.

JONAS H. SMITH, OF LISTOWELL, ONTARIO, CANADA.

BOSS FOR TEA-KETTLE SPOUTS.

SPECIFICATION forming part of Letters Patent No. 244,402, dated July 19, 1881.

Application filed January 20, 1881. (No model.)

To all whom it may concern:

Be it known that I, JONAS HENRY SMITH, of Listowell, in the county of Perth, in the Province of Ontario, Dominion of Canada, have invented a certain new and useful Boss for Tea-Kettle Spouts; and I do hereby declare that the following is a full, clear, and exact description of the construction and operation of the same.

10 My invention relates to a very simple yet effective device for preventing the spout of a tea-kettle from being worn, indented, or destroyed by the constant hard usage it is daily subjected to in the kitchen.

15 My invention consists in constructing a boss pressed of heavy tinned sheet iron or copper corrugated and formed to fit a tea-kettle spout, and soldering or riveting the same to the kettle.

By reference to the drawings it will be seen

that A, Figure 1, represents a side view of a tea-kettle; B, the spout; C, the corrugated boss; D, a flange at the lower portion of the boss, which is securely fastened, by soldering, riveting, or both, to the kettle.

Fig. 2 is a perspective view of the boss and its flange.

What I claim as my invention is—

The combination, with a tea-kettle spout, B, of a corrugated metallic boss, C, the same being made to fit and be secured to the spout and kettle, substantially as and for the purpose specified.

Dated at Listowell, Ontario, Canada, this 24th day of December, 1880.

J. H. SMITH.

In presence of—

HENRY SANDERSON,

THOMAS GOODFELLOW.
